UNITED STATES PATENT OFFICE.

BENJAMIN F. KLEIN, OF CHICAGO, ILLINOIS.

GAME OF SKILL.

Application filed March 29, 1923. Serial No. 628,413.

To all whom it may concern:

Be it known that I, BENJAMIN F. KLEIN, a citizen of the United States, a resident of Chicago, in the county of Cook and State 5 of Illinois, have invented a certain new and useful Improvement in Games of Skill, of which the following is a full, clear, concise, and exact description, reference being had to the accompanying drawings, forming a 10 part of this specification.

My invention relates to a game of skill and apparatus for playing the same.

The nationally popular game of golf requires a large investment in grounds, and 15 the upkeep of such grounds is a large item of expense. In addition to that, each individual player must own a relatively expensive outfit of clubs. As the ball is driven directly from the ground, weather conditions frequently make it impossible to play.

One primary object of my invention is the elimination of the above mentioned objections.

Another object is to provide for playing 25 a game involving substantially all the elements of skill, excitement, and healthful exercise possessed by golf.

Further objects and advantages of the invention will become apparent as the description proceeds.

In the accompanying drawings:

Fig. 1 is an elevation of an objective standard;

Fig. 2 is an elevation of a propelling standard;

Fig. 3 is a plan view of a bat;

Fig. 4 is a section on line 4—4 of Fig. 1;

Fig. 5 is a section on line 5—5 of Fig. 4;

Fig. 6 is a section on line 6—6 of Fig. 2;

Fig. 7 is a section on line 7—7 of Fig. 6;

Fig. 8 is a section on line 8—8 of Fig. 3;

Fig. 9 is a similar section illustrating another driver;

Fig. 10 is a section of a supporting base.

In the embodiment of apparatus according to the invention selected for illustration, the objective standard 10 and propelling standard 12 are of sectional construction, comprising duplicate ground engaging sections 14, and duplicate extension sections 16, of which two are employed for the objective and preferably only one for the propelling standards.

The type of sectional joint construction I have so far found it preferable to employ, is clearly illustrated in Fig. 5, and comprises

a pin 18 projecting from the lower end of each extension section, and a socket 20 formed at the upper end of each ground engaging section as well as at the upper ends 60 of all the extension sections. The lower ends of the ground engaging sections are pointed for ready insertion into the ground to support the standard, or for entry into socket 22 (see Fig. 10) in base 24, which 65 base may be employed in playing over ground not suitable for penetration by the pointed ends of sections 14.

A cross-arm 26 completes the propelling standard 12. This cross-arm is provided 70 with a rigid pin 28 adapted to enter the top socket 20 and support the arm. I have illustrated sling means 30 in the nature of a strip of rubber hanging below cross-arm 26 to support ball 32. The ends of the strip are 75 preferably securely fastened to the end of the cross-arm, as by means of washers 34 cemented to the strip and to the cross-arm. The lowest portion of the strip is apertured at 34 so that it will spread slightly and 80 securely support the ball in place.

The objective standard illustrated comprises a ground engaging section 14 surrounded by two extension sections 16. A suitable mesh basket 36 depending from 85 supporting ring 38 is mounted on the standard by means of concentric sleeves 40 and 42 telescoping on one of the extension sections 16, and receiving the downwardly turned ends 44 of wire 38 between them. It will 90 be noted that the outer diameter of socket 20 is greater than that of section 16, so that the end of the socket member affords a shoulder for abutment with the sleeves to limit their downward displacement. In assembling the standard, the basket can 95 obviously be slipped on either section 16, and will be held just above the top of the section below. To complete the objective standard I provide a suitable signal or flag 46 having 100 a standard 48 shaped to fit in the topmost socket 20. This signal can be seen at a greater distance than the standard itself to facilitate playing to the standard from a remote point.

The bat illustrated in Figure 3 comprises a handle member 50 and a head 52, into which a facing 54 of resilient material, such as sponge rubber, is set. Another type of bat more efficient for distance driving, is 110 illustrated in Figure 9, and comprises an annular or cup-shaped head 56 apertured

at 58 to provide communication with the air space inside. The face of this bat is covered with a resilient diaphragm 60 clamped to the head at 62 and tensioned by a ring 64 forced up against it by adjusting set-screws 66.

To play the game, objective standard 10 is set up as indicated in Figure 1, and the player positions himself at a remote point 10 with the bat and the propelling standard of Figure 2. It will be obvious that the nature of the terrain over which the ball must travel need only be such that it will be possible to find the ball after it has been driven. The propelling standard is set up, and ball 32 placed in position in sling 30. The player can now strike the ball forward and upward at an appropriate angle. I have been able to drive balls of hollow rubber or of cork from 50 to 75 yards.

The player now picks up standard 12 and proceeds to the point where the ball comes to rest, counting one stroke. The propelling standard is set up again, and this process is repeated until the ball comes within a relatively small distance of the objective standard. In doing this I have found that the flight of the ball is subject to pull and slice, precisely as that of an ordinary golf ball. If a clumsy player fails to strike true, he is not apt to do more than stretch the rubber of the sling somewhat, and at the worst, he would only tip over the standard.

When the ball is near enough to the objective standard, the player may try for a basket. This merely calls for less force and a steeper angle in striking the ball. If the first attempt fails, the ball will ordinarily come to rest nearer the bracket than before, and successive attempts are made until the ball is in the basket.

The preferable system for a game with two players will be for each player to set up his objective standard, the standards being separated by the distance mutually agreed upon. Both players then start from one objective standard and play to the other, and back again as often as desired.

With more than two players the standards may be set up to form a regular or irregular polygon and all the players can play round the same, either in one group or a plurality of groups.

It will be obvious, that standard 12, either with or without taking the sections apart, may be carried by the player with less exertion than is required to carry an ordinary bag of golf clubs, but that the apparatus

illustrated renders the player entirely independent of nearly all the ordinary limitations and expenses incident to playing golf.

Without further elaboration, the foregoing will so fully illustrate the gist of my invention, that others may, by applying current knowledge, readily adapt the same for use under various conditions of service. It will, for instance, be obvious that the ball might be propelled from the point where the propelling standard 12 is located by whirling it in a sling, by stretching an elastic sling to throw the ball by the reaction of the sling itself, by various mechanisms, or even by throwing it. These and many other modifications and adaptations may readily be made without eliminating certain features which may properly be said to constitute the essential items of novelty involved, which items are intended to be defined and secured to me by the following claims.

I claim:

1. Apparatus for playing a game of skill, comprising an objective standard and a propelling standard, a basket on said objective standard, and a sling on said propelling standard for supporting a ball.

2. Apparatus for playing a game of skill, comprising sectional, objective and propelling standards, said sections including two interchangeable ground-engaging sections, and a plurality of interchangeable extension sections.

3. Apparatus for playing a game of skill, comprising a standard, a cross-arm on said standard, and a sheet rubber sling hanging below said cross-arm to support a ball.

4. Apparatus for playing a game of skill, comprising a standard, a cross-arm on said standard, and a sheet rubber sling hanging below said cross-arm to support a ball, said sling having a perforation at its lowest portion to seat said ball.

5. Apparatus for playing a game of skill, comprising interchangeable sectional standards having duplicate pin and socket joints, a cross-arm having a pin at one end to enter one of said sockets and support the arm, a basket, a sleeve supporting said basket and shaped to telescope on any section and abut the socket of a section below, and a signal having a standard insertable in said socket.

In witness whereof, I hereunto subscribe my name this 27 day of March, 1923.

BENJAMIN F. KLEIN.
